(57) **CLAIM**

The ornamental design for scissors, as shown and described.

DESCRIPTION

FIG. 1 is a front view of scissors showing my new design,

FIG. 2 is a rear view thereof,

FIG. 3 is a top view thereof,

FIG. 4 is a bottom view thereof,

FIG. 5 is a right side view thereof,

FIG. 6 is a left side view thereof,

FIG. 7 is a cross-sectional view thereof taken along 7—7 line of FIG. 1; and,

FIG. 8 is a perspective view thereof.

The broken lines shown on the drawings are for illustrative purposes only and form no part of the claimed design.
